UNITED STATES PATENT OFFICE

MAX KLINE, OF BRONX, NEW YORK

DESIGN FOR A COMPACT OR THE LIKE

Application filed May 31, 1930. Serial No. 35,877. Term of patent 3½ years.

To all whom it may concern:

Be it known that I, MAX KLINE, a citizen of the United States, residing at the Bronx, in the county of Bronx and State of New York, have invented a new, original, and ornamental Design for a Compact or the like, of which the following is a specification, reference being had to the accompanying drawing, forming part thereof.

The figure is a perspective view of a compact showing my new design.

The essential feature of my design consists in the ornamentation on the cover. The surface of the reverse cover portion is plain and unornamented.

I claim:

The ornamental design for a compact or the like, as shown and described.

MAX KLINE.
